UNITED STATES PATENT OFFICE.

GUSTAVE A. KING, OF CHICAGO, ILLINOIS.

TWEEZERS.

Application filed July 10, 1922. Serial No. 573,771.

To all whom it may concern:

Be it known that I, GUSTAVE A. KING, a citizen of the United States, residing at Chicago, in the county of Cook and State of Illinois, have invented new and useful Improvements in Tweezers, of which the following is a specification.

This invention relates to tools of the tweezers type, and its object is to produce a tool of this kind which is very simple in construction, and therefore capable of being easily and cheaply manufactured.

The invention also has for its object to provide a tool of the kind stated which will firmly and automatically hold the object grasped thereby.

With the objects stated in view, the invention consists in a novel combination and arrangement of parts to be hereinafter described and claimed, and in order that the same may be better understood, reference is had to the accompanying drawing, wherein:

Figure 1 is a perspective view of the tool; Fig. 2 is a section on the line 2—2 of Fig. 1. Fig. 3 is a view similar to Fig. 1 showing a modification, and Fig. 4 is a section on the line 4—4 of Fig. 3.

Referring specifically to the drawing, the tool is constructed of a single strip of spring metal which is bent intermediate its ends to form two spring arms 10, the free end portions 11 of which are the jaws of the tool. The arms 10 are laterally spaced and near the end portions 11 they are brought together and loosely connected. The connection, as shown in Figs. 1 and 2, is a rivet consisting of a shank 12 and heads 13. Forwardly of this rivet, the end portions 11 are bowed outwardly or away from each other, with their extremities or tips coming together.

The arms 10, due to their inherent resiliency, have a normal tendency to spread, which, owing to the connection between the end portions 11 thereof, keeps the extremities thereof in contact, and hence the jaws formed by said end portions are normally closed. To open the jaws, it is necessary only to press together the arms 10 some distance back of the connection. This action causes the jaws to spread or open up as shown dotted in Fig. 2, to grasp the object to be held, and upon releasing the arms 10, they automatically spread and cause the jaws to close up and firmly grip to object.

In order that the rivet heads 13 may not interfere with this movement of the arms 10 and the jaw portions 11, said heads have their surfaces which are next to the arms and jaw portions beveled in opposite directions, as shown in Fig. 2.

Figs. 3 and 4 show a different connection between the arms 10. Here, a sleeve 14 is employed which envelops the arms, and is flared from a point midway between its ends 65 in the direction of each end, to permit the hereinbefore play of the arms and the jaw portions thereof.

The loop 15 connecting the arms 10 enables the tool to be hung on one's finger with 70 an object in its grasp, so as to be handy for the work in progress.

I claim:

1. A gripping tool comprising connected 75 spring arms, the forward portions of which are curved inwardly to define opposed rounded contact surfaces, the portions of said arms in advance of said opposed rounded contact surfaces being bowed and having their extremities normally in contact, and means connecting the arms at the said inwardly curved forward end portions of the same, whereby the said rounded contact surfaces are maintained flatly in engagement with each other. 80

2. A gripping tool comprising connected 85 spring arms, the forward portions of which are curved inwardly to define opposed rounded contact surfaces, the portions of said arms in advance of said opposed 90 rounded contact surfaces being bowed and having their extremities normally in contact, and a pin extending through and loosely connecting the arms at the said inwardly curved forward end portions of the same 95 and having heads, the inner sides of which are rounded to conform to the curvature of the adjacent portions of said arms.

3. A gripping tool comprising connected 100 spring arms, the forward portions of which are bowed inwardly to define opposed rounded contact surfaces, the portions of said arms in advance of said opposed rounded contact surfaces being bowed outwardly and having their forward extremities normally in contact. 105

In testimony whereof I affix my signature,

GUSTAVE A. KING.
